UNITED STATES PATENT OFFICE.

FRED W. COOK, OF MICHIGAN CITY, INDIANA, ASSIGNOR TO PERFECTION COOLER COMPANY, OF MICHIGAN CITY, INDIANA.

DESIGN FOR A LIQUID-COOLER BOTTLE.

Application filed April 2, 1928. Serial No. 26,092. Term of patent 14 years.

To all whom it may concern:

Be it known that I, FRED W. COOK, a citizen of the United States, residing at Michigan City, in the county of Laporte and State of Indiana, have invented a new, original, and ornamental Design for Liquid-Cooler Bottles, of which the following is a specification, reference being had therein to the accompanying drawings.

In the accompanying drawing:

Figure 1 is a side elevation showing my new design.

Figure 2 is a top plan view of Figure 1.
Figure 3 is a central cross sectional view of Figure 1.

Figure 4 is a central longitudinal sectional view of Figure 1.

I claim:

The ornamental design for a liquid cooler bottle as shown.

In testimony whereof I hereunto affix my signature.

FRED W. COOK.
